UNITED STATES PATENT OFFICE

FREDRICK W. CLEMENT, OF WORCESTER, MASSACHUSETTS, ASSIGNOR TO FRANK HOLTON & CO., OF CHICAGO, ILLINOIS, A CORPORATION OF ILLINOIS.

DESIGN FOR A CORNET.

43,815.

Specification for Design.

Patented Apr. 8, 1913.

Application filed December 30, 1911. Serial No. 668,776. Term of patent 14 years.

To all whom it may concern:

Be it known that I, FREDRICK W. CLEMENT, a citizen of the United States, residing at Worcester, in the county of Worcester and State of Massachusetts, have invented a new, original, and ornamental Design for Cornets, of which the following is a specification, reference being had to the accompanying drawing, forming a part thereof.

Figure 1 is a side elevation of a cornet,

showing my new and original design; Fig. 2 is a bottom plan view of the instrument illustrated in Fig. 1.

I claim:

The ornamental design for a cornet as shown.

FREDRICK W. CLEMENT.

Witnesses:

INEZ F. PENNIMAN,

WILLIS E. SIBLEY.
